SELF-COMPENSATING MEANS FOR MAKE
AND BREAK CIRCUITS

Harve R. Stuart, Springfield, Ohio

Application January 19, 1946, Serial No. 642,405

5 Claims. (Cl. 123—148)

1

The present invention broadly relates to self-regulating means for inherently improving the performance of current interrupter contacts, and is more particularly directed to correcting certain deficiencies in conventional circuits being used for electric ignition in internal combustion engines.

The primary object of this invention is to provide electro-magnetic compensating control means for variable speed automotive engines or the like that are frequently run under widely varying speed conditions, said means at slow breaker frequency being adapted to automatically decrease the initial current flow and protracted intensive arcing at the interrupter contact points to reduce the wear rate thereof, and if desired to automatically boost current flow to progressively and automatically augment the intensity of an ignition jump spark as the breaker frequency rate is increased.

A further object is to accomplish the cited purpose by inherent means inbuilt or compactly installed as an accessory to existing types of ignition distributors without need of any mechanical manipulation to attain a more advantageous control of current flow at said contact points over conventional practice.

Embodied herein are illustrative circuit arrangements that will hereinafter be more explicitly set forth. Reference is had to the accompanying sheet of drawings that discloses a preferred embodiment of my invention, and in which drawings:

Fig. 1 is an elevational view taken in part section along line I—I of Fig. 2, that shows my compensating means applied to a well known automotive distributor or ignition timer, a portion of the preferred wiring system being incorporated alongside such sectional view.

Fig. 2 represents a detail taken along 2—2 of Fig. 1 with half of the distributor cap removed.

Fig. 3 schematically presents a wiring diagram for the Fig. 1 type of distributor.

Referring more specifically to Figs. 1—3, this type is particularly adapted to variable speed needs and as such may comprise a conventional automotive ignition distributor system including a fixedly mounted base or bottom head 10 equipped with a central bearing 11 and a cylindrical skirt portion 12 affording an upturned mouth. A vertical distributor shaft 14 is mounted in said bearing and its lower end provided with a driven coupling 15 that may be gear connected to rotate in unison with the engine speed.

A disc 16 may be inset into the mouth of the

2

skirt 12. Above such disc, the shaft 14 may carry a multi-lobed circuit breaker cam 17, the one shown being of octagonal contour adapted to handle an eight cylinder engine. Mounted upon said disc is an insulated, laterally resilient circuit breaker lever 18 which is cam actuated about the insulated fulcrum 19 by the intermediate cam follower 20. A swinging end of such lever is provided with an interrupter contact point 22. Cooperating therewith is a mated anvil or opposed contact point 23 that is usually grounded to the framework. An insulated terminal lug 24 may be flexibly connected to the contact 22 through a spring 9 and said lever 18 which is also wired at 8 to connect with a conventional shock condenser 25 whose casing may be grounded. The use of such condenser is deemed essential for a commercially acceptable performance as applied to jump spark ignition in automotive engines.

20 The crown of the shaft 14 may have demountably affixed thereto, an insulated distributor arm 26 which may be maintained in contact with the high tension electrode 27 that is retractively mounted in a bell-shaped plastic cap 28. Also carried by such cap, are one or more wiped brushes such as 29, their number being dependent upon the profile given to the cam 17. These brushes are successively contacted by the arm 26. Each such brush may be separately wired at 30 to a distinctive jump spark plug 31 in a conventional manner.

Another timer circuit (see Fig. 1 diagram) is comprised in the lead wire 32 extending from the electrode 27 to the ignition or the like induction coil 33 having the primary winding 34, a core 35 and a secondary high tension winding 36. Corresponding terminals of such superimposed windings may be interconnected by the lead wire 37 and carried to an electrical energizing source such as the storage battery 38 that in automotive practice is commonly grounded at G. A dash controlled ignition switch 39 usually commands current flow to the primary winding 34, the opposite terminal of said primary winding being carried by the lead wire 21 to the lug 24.

The foregoing description relates to a conventional electrical hook-up for a combined current interrupter and distributor commonly employed in variable speed automotive engines. An inherent defect thereof lies at slow distributor speed in rapid wear by destructive arcing at the primary contact points 22 and 23. In order to remedy these deficiencies, I preferably resort to the supplementary electrical compensating means shown in Fig. 1.

Such preferred corrective may be introduced in the defined conventional distributor lead wire 21 by the use of a compensating primary winding 40 in conjunction with a secondary winding 41 which is wound in opposition to its primary winding to co-operate with a soft iron core 42 common to both such windings in transformer fashion. Said primary winding 40 is connected in series with a primary winding 34 of the induction coil. The secondary winding 41 is preferably shunt connected across the lead wires 21 and 37, there being an additional compensating condenser 43 interposed in series with such shunt, as shown.

Upon closing the circuit breaker points 22 and 23, current will flow from the battery 38 through the coils 40 and 34. This in turn magnetizes the cores 42 and 35 and induces a potential in such direction as to assist the battery potential in charging the condenser 43. When the latter becomes fully charged, current ceases to flow through the coil 41. Thus the work done by the initial current inrush through the coil 40 momentarily increases the impedance of said coil 40 and effects a reduction in the initial current flow through the circuit including the circuit breaker points 22 and 23.

The iron cores 42 and 35 remain magnetized so long as these points remain closed. Upon opening the timed breaker points, the battery current through the coils 40 and 34 is stopped, whereby the magnetism of both iron cores 35 and 42 collapses and thus inducing a potential in coils 34, 36, 40 and 41.

The potential induced in coil 34 is in a direction to pass current through the battery 38 from negative to positive to assist the battery potential in charging the shock condenser 25, while at the same time tending to raise the potential of the condenser 43.

The potential induced in coil 41 is in a direction to further add to the potential of the condenser 43 and therefore tends to remain the potential of the interrupter contact 22 as it breaks the circuit at the points 22 and 23. Because of such transient action, the condenser 43 does not maintain its charge after the points 22 and 23 are completely separated but said charge may oscillatively equalize through the coils 40, 41 and 34. As will be understood, the condenser 25, coil 34 and the battery 38 function in conventional fashion in causing a spark to jump the gap of the spark plug 31.

These various components of my distributor system may have different time constants. When sufficient time elapses between the closing and opening of such circuit, certain transient effects such as the current flow to the condenser 43 may have ceased and all other conditions may have become stable before another cycle is begun.

As the cyclic frequency is increased, the time consumed in charging and discharging the auxiliary condenser 43 may finally coincide with its natural period and almost exactly counteract the instantaneous impedance of coil 40. Upon a still further increase of frequency, the charging current to the condenser 43 may assist the battery current then flowing through coil 34 and thus increase the useful high tension spark voltage above that which would obtain by the use of conventional means.

It might be observed that the constants of my electro-magnetic system may remain fixed and that therefore the electrical performance may be materially affected by changes in periodic

frequency. Accordingly different phase relations of current and potential may result when the breaker points operate at widely different frequency. By proper proportioning, said system may be designed to "buck" current flow at one frequency and to "boost" the same at some other frequency, preferably in an inherently self-regulating or automatic manner without need of extraneous impedance adjustment.

Furthermore, assuming the use of an inserted choking transformer and combined condenser of proper capacity, the relative current flow through the closed interrupter contacts may without jeopardy be increased as the rate of cam revolutions is raised to provide a self-regulating, gradually augmented engine ignition spark that affords a minimum of contact wear under adverse slow speed running conditions.

Accordingly, my auxiliary transformer elements 40, 41 and 42 together with the condenser 43, may at high speeds serve as a spark booster. All such compensating components may be compactly assembled as an accessory unit and as such readily be incorporated into existing conventional distributor circuits. It will be obvious that for single or multicylinder engine purposes, the same principle underlying my self-regulating circuit may likewise be applied to different needs such as any pulsating or intermittent current generated by means of a circuit interrupting device.

It is thought the foregoing disclosures will make evident to those skilled in this art, the more outstanding advantages afforded over the prior art by my improved automatic compensating means, also that various equivalent modifications in my illustrative exemplification may be applied in obtaining a similar result, all without departing from the spirit and scope of my invention as more particularly characterized in the appended claims.

I claim:

1. In a circuit breaker device, the combination of a pair of current interrupter contacts, means for making and breaking said contacts in sequence, a choke condenser shunted across the broken contacts, an induction coil comprising an electrically energized primary winding and a secondary winding, said contacts being respectively wired to the opposed terminals of said primary winding to complete a circuit therethrough when the contacts are closed, and supplementary electrical compensation means comprising a primary winding, a cooperating secondary winding and an additional condenser, the primary winding of the compensating means being connected in series with the primary winding of the induction coil and the secondary winding of the compensating means being shunted across the aforesaid series connected primary windings and having the last named condenser incorporated into such shunted cross connection.

2. In a circuit breaker for jump spark ignition of a multicylinder internal combustion engine, the combination of a pair of current interrupter contacts, rotatable cam means operatively disposed to repeatedly make and break said contacts, a shock condenser shunted across the broken contacts, a distributor device provided with a distributor arm arranged to shift in synchronism with the cam means and further provided with a plurality of high tension brushes that are contacted in sequence by said arm, a separate spark plug independently wired to each such brush, an induction coil comprising an electrically energized primary winding and a secondary winding

ing, the latter having a terminal connected to said arm and the interrupter contacts being respectively wired to opposed terminals of said primary winding to complete a circuit therethrough when said contacts are closed, and self-regulating electrical compensating means comprising a primary winding, a cooperative secondary winding and an additional condenser, the primary winding of the compensating means being connected in series with the primary winding of the induction coil and the secondary winding of the compensating means being shunted across the aforesaid series connected primary windings and having the last named condenser incorporated in such shunted cross connection, said compensating means serving to effect a relatively intense choking action to current flow through said completed circuit while the engine is run at comparatively slow speed and to progressively reduce such choking action with increased engine speed without need of impedance adjustment.

3. A circuit breaker comprising a pair of current interrupter contacts timed by a distributor for successively igniting explosive charges in a variable speed multicylinder internal combustion engine, a shock condenser shunted across said contacts, an induction coil having a primary winding and a secondary winding both cooperatively coiled about a common magnetic core, and compensating electrical means comprising a supplementary primary winding that encircles another magnetic core and is connected in series with the primary of said coil and which compensating means further include separate secondary winding means subject to the inductive influence of the last named core and which winding means is shunt wired across the respective outer terminals of the aforesaid series of primary windings with an additional condenser incorporated in said shunt wiring.

4. A circuit breaker comprising a pair of current interrupter contacts timed by a distributor for successively igniting explosive charges in a variable speed multicylinder internal combustion engine, a shock condenser shunted across said contacts, an induction coil having a primary winding and a secondary winding both coopera-

tively coiled about a common magnetic core, and compensating electrical means comprising an auxiliary condenser together with a supplementary primary winding that encircles another magnetic core and is connected in series with the primary of said coil and which compensating means further include separate secondary winding means subject to the inductive influence of the last named core and which winding means is shunt connected across the respective outer terminals of the aforesaid series of primary windings whereby to modify the output of the secondary winding of the induction coil at different breaker frequencies.

5. In a circuit breaker device, the combination of mated current interrupter contacts, means for successively making and breaking said contacts, a shock condenser shunted across the breaker contacts, an induction coil comprising an electrically energized primary winding and a secondary winding, said contacts being respectively wired to the opposed terminals of said primary winding to complete a circuit therethrough when the contacts are closed, and supplementary electrical compensating means comprising an auxiliary condenser together with a primary winding and a cooperating secondary winding of which both windings surround a common magnetic core, the primary winding of said compensating means being connected in series with the primary windings of the induction coil and the secondary winding of the compensating means being shunted across the outer terminals of the aforesaid series connected primary windings.
